UNITED STATES PATENT OFFICE.

MARTIN L. SCANLAN, OF LOUISVILLE, KENTUCKY.

DETACHABLE FIRE-FRONT.

SPECIFICATION forming part of Letters Patent No. 624,984, dated May 16, 1899.

Application filed November 3, 1898. Serial No. 695,408. (No model.)

To all whom it may concern:

Be it known that I, MARTIN L. SCANLAN, a citizen of the United States, residing at Louisville, in the county of Jefferson and State of Kentucky, have invented certain new and useful Improvements in Detachable Fireplace-Fronts, of which the following is a specification.

The object of my invention is to provide a cover for a fireplace which shall not only conceal the cavity containing the grate, but which shall also conceal the frame or molding surrounding the cavity. Not only do the grate and the fireplace proper become blackened and marred after use during the winter, but the arched molding or frame surrounding the opening is also discolored.

I have provided a cover which entirely closes the fireplace-opening, thus concealing the interior thereof, and which is formed with a hollow rib on its edges which fits over the arched molding and conceals it, so that when the fireplace is not in use, as in the summer, it will present an attractive appearance.

I have provided also improved devices for attaching the detachable front to the fireplace, which are so constructed as to securely hold it in place, but which can be easily operated to release the front and permit its removal.

In the accompanying drawings, Figure 1 is a front elevation of a mantel and fireplace with my improvement applied. Fig. 2 shows, on an enlarged scale, a transverse section on the line 2 2 of Fig. 1, looking in the direction indicated by the arrows. Fig. 3 is a perspective view of the molding or frame surrounding the opening of the fireplace. Fig. 4 is a perspective view of my improved detachable front. Fig. 5 is a detail view, on an enlarged scale and in section, on the line 5 5 of Fig. 1, showing particularly my improved fastening device.

The fireplace A may be of the usual construction and may be lined, as usual, with metallic plates B. These plates are flanged at b, and to these flanges is secured an arched or three-part frame C. This frame on its rear side is provided with grooves or recesses c for a purpose hereinafter described.

The detachable front or cover D is preferably made of sheet metal; but it may be

made of stiff cardboard or other suitable material or a combination of materials. It is provided with suitable handles d', and three of its edges d are made in the form of a hollow molding or rib corresponding in shape to that of the arched frame C. The cover D closes the front of the fireplace-opening, as illustrated in Figs. 1 and 2, while the hollow rib d completely covers the arched frame or molding C. This front piece may be secured to the fireplace in any suitable way; but I prefer to use the devices illustrated. These consist of two spring-catches E, preferably arranged on opposite sides of the front piece about midway between its upper and lower ends, as shown in Fig. 1. Each of these catches consists of a bent arm e', which is pivoted at e⁸ to a bracket e, having an arm e⁹ extending into a recess or groove c in the molding C, in which it is secured by a screw e¹⁰. The arm e' is formed with a tailpiece e¹¹, against which bears the end of a spring e¹², secured to the bracket e by a rivet e¹³. The outer or front end of the arm e' is bent at e⁷, so that it may be readily manipulated when it is desired to remove the front D. The construction is such that the spring e¹² holds the arm e' tightly against the hollow rib of molding d when the detachable front is in place. The arm, however, can be swung outwardly against the force of the spring e¹², and when moved to a sufficient extent the spring will engage the tailpiece e¹¹ and hold the arm open in its outer position.

The fireplace and the molding C are of the usual construction, and the front D is adapted to be applied to the usual form of fireplace. It may be made of a size adapted for different sizes of fireplaces, and the rib or molding d may be made of suitable size and shape to fit any style of molding surrounding the fireplace-opening. The front D may be formed with any ornamentation desired to give it an attractive appearance.

I claim as my invention—

1. The combination with a fireplace having a molding around its front edge, of a detachable front or cover, provided with a hollow rib or molding around its edge adapted to fit over and conceal the molding around the edge of the fireplace.

2. The combination with a fireplace having

a molding around its front edge, of a detachable front or cover, provided with a hollow rib or molding around its edge adapted to fit over and conceal the molding around the edge of the fireplace, and spring-catches arranged on opposite sides of the fireplace and adapted to engage with the detachable front or cover.

3. The combination of the fireplace having a molding surrounding its front edge, of a detachable cover or front having a hollow rib or molding adapted to cover and conceal the molding of the fireplace, and spring-catches

holding the detachable front in place, each comprising a bracket, a pivoted arm mounted on the bracket, and a spring bearing on the arm and adapted to hold it in either its open or closed position.

In testimony whereof I have hereunto subscribed my name.

MARTIN L. SCANLAN.
